DESIGN.

—o—
O. HEINIGKE.

CARPET.

No. 15,974.

Patented Mar. 17, 1885.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 15,974, dated March 17, 1885.

Application filed January 14, 1883. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The face of the design is closely filled in with variously-massed flower and leaf groups without continuous connection. In the lower

center of the photograph is a large thick mass of flowers and leaves, showing three large open flowers conspicuously and dotted leaves below. On the left of the photograph above is a group showing long flag-like leaves. The center and upper part of the design has a light ground, and around it is a dark ground, the one running into the other in moss-like projections.

I claim—

The design for a carpet, substantially as shown and described.

OTTO HEINIGKE.
